Richard B. Queen, ATTORNEY.

UNITED STATES PATENT OFFICE.

WILLIAM H. BRADLEY, OF CONCORD, NEW HAMPSHIRE.

CURTAIN-FIXTURE.

1,307,292.

Specification of Letters Patent. Patented June 17, 1919.

Application filed January 9, 1919. Serial No. 270,411.

To all whom it may concern:

Be it known that I, WILLIAM H. BRADLEY, a citizen of the United States, residing at Concord, in the county of Merrimack and 5 State of New Hampshire, have invented certain new and useful Improvements in Curtain-Fixtures, of which the following is a specification.

This invention relates to curtain fixtures.

10 The main object of the invention is to provide a simple and inexpensive device of this character by the use of which, shade rollers may be raised and lowered without danger of the spring being broken.

15 Another object is to provide a fixture of this character for use with shade rollers having no springs or in which the springs have been broken.

With the foregoing and other objects in 20 view, which will appear as the description proceeds, the invention resides in the combination and arrangement of parts and in the details of construction hereinafter described and claimed, it being understood that 25 changes in the precise embodiment of the invention herein disclosed may be made within the scope of what is claimed without departing from the spirit of the invention.

In the accompanying drawings:—

30 Figure 1 represents a front elevation of a pair of fixtures constructed in accordance with this invention shown applied with parts broken out for convenience in illustration,

Fig. 2 is a transverse vertical section taken 35 on the line 2—2 of Fig. 1,

Fig. 3 is a detail front elevation of the spring carried fixture with the inclosing casing removed,

Fig. 4 is a transverse section taken on the 40 line 4—4 of Fig. 3, and

Fig. 5 is a detail sectional view taken on the line 5—5 of Fig. 4.

In the embodiment illustrated, a pair of fixtures 1 and 30 are shown mounted at the 45 opposite sides of a window frame F in the usual manner, it being obvious that the fixtures may be made to be applied on the reverse sides of the frame if found desirable.

The fixture 1 comprises a base plate 2 of 50 metal sufficiently heavy to be rigid and which is designed to lie flat against the outer face of frame F. An attaching plate 3 extends rearwardly at right angles from the lower edge of plate 2, its free edge being 55 preferably sharpened to facilitate its insertion between the window frame F and a

casing C as is shown clearly in Fig. 2 and thereby avoid marring of the frame by attaching elements, or it may be inserted between any suitable members.

Projecting forward from plate 2 at right angles thereto is an arm 4 extending from the upper edge of said plate and provided at its front end with a curtain pole receiving seat 5.

60 Inclosed in a casing 6 are two laterally projecting longitudinally spaced journal posts or plates 7 and 8 spaced apart any suitable or desired distance according to the size of the parts to be mounted between them. A shaft 9 is journaled between plates 7 and 8 and has fixed thereon a gear wheel 10, at one side of which is mounted a coiled spring 11 similar to an ordinary clock spring, one end being fixed to shaft 9 and the other to a pin 75 or stud 12 projecting from plate 7 as is shown clearly in Fig. 4. This gear 10 meshes with a pinion 14 carried by a shaft 13 also journaled in plates 7 and 8, the inner end of said shaft projecting beyond plate 8 for a 80 purpose presently to be described.

85 Mounted on plate 8 is a casing 15 in which are pivotally mounted two pawls 16 and 17 which are designed to alternately engage a ratchet 18 fixed on shaft 13 for holding the shade roller in adjusted position in the manner usual in devices of this character.

90 The projecting end of shaft 13 has an angular socket 19 in its terminal and a longitudinal slot 20 at the rear of said socket 90 through which extends a pin 22 carried by a sliding collar 21. A coiled spiral spring 23 is also mounted on shaft 13 between the journal plate 8 and the rear end of collar 21 and exerts its tension to normally force 95 said collar outward to cover the pintle P of the shade roller R which is designed to be mounted in socket 19 as is shown clearly in Fig. 3 and thereby prevent all danger of the pintle becoming disengaged from the 100 socket.

105 The fixture 30 shown at the right of Fig. 1 is designed to support the cylindrical pintle P' of the shade roller R and to provide for the adjustment of the two fixtures toward or away from each other, the base plate 31 of this fixture is longitudinally slotted as shown at 32 and 33 to receive laterally projecting studs 34 carried by the fixture which supports pintle P', it being 110 obvious that the fixture 36 may be adjusted in the slots 32 and 33 and held at any de-

sired position thereon by any suitable means, thumb nuts being preferably provided on the rear ends of the studs 34.

From the above description it will be obvious that a shade roller R having an angular pintle P at one end and a round pintle P' at its other end, may be mounted in the fixtures 1 and 30 and the shade S raised or lowered in a manner ordinary with spring roller shades of this character.

From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

Having thus fully described my invention, what I claim as new and desire to secure by Letters Patent, is:

1. A fixture of the class described comprising a pair of brackets having frame engaging means, a shaft carried by one of said brackets having pintle receiving means, a collar slidable on said shaft, to fit over the pintle and hold it engaged with the shaft, and means for retaining said collar in operative position.

2. A fixture of the class described comprising a pair of brackets having frame engaging means, a shaft carried by one of said brackets having pintle receiving means, a collar slidable on said shaft to fit over the pintle and hold it engaged with the shaft, and a spring for forcing said collar outward.

3. A fixture of the class described comprising a base plate, an attaching plate carried thereby, supports carried by said base plate, spring controlled gearing mounted on said supports, a shaft having pintle receiving means connected to be operated by said spring through said gears, and spring pressed means on said shaft to hold the pintle engaged therewith.

4. A fixture of the class described comprising a base plate, an attaching plate carried thereby, supports carried by said base plate, spring controlled gearing mounted on said supports, a shaft having pintle receiving means connected to be operated by said spring through said gears, a collar slidable on said shaft to fit over the pintle and hold it engaged with the shaft, and a spring for forcing said collar outward.

In testimony whereof I affix my signature in presence of two witnesses.

WILLIAM H. BRADLEY.
